ATTORNEY.

UNITED STATES PATENT OFFICE.

JOHN B. MARTIN, OF CINCINNATI, OHIO.

SCRUBBING-BRUSH.

SPECIFICATION forming part of Letters Patent No. 714,215, dated November 25, 1902.

Application filed August 16, 1902. Serial No. 119,938. (No model.)

To all whom it may concern:

Be it known that I, JOHN B. MARTIN, a citizen of the United States, and a resident of the city of Cincinnati, in the county of Hamilton and State of Ohio, have invented certain new and useful Improvements in Scrubbing-Brushes, of which the following is a specification.

Among the various objects of my invention 10 may be mentioned the following, to wit: first, to provide a cleaning and scrubbing brush exceedingly simple in construction and useful and convenient in operation, with a duplexscraper for removing resistfulsubstances 15 on the plane surface of floors and wood-work and four sharp corners for cleaning out grooves and crevices; secondly, to provide a brush wherein a duplex four-cornered scraper is formed upon one or both ends of 20 the back of cleaning and scrubbing brushes, all of which are integral with the back of brush; thirdly, to secure compactness of construction, and under this head to secure such a construction as that the scraping-points 25 shall require no more room than would the back when these scrapers were absent; fourthly, to secure cheapness and economy of manufacture; fifthly, to secure convenience in use; sixthly, to obtain a device which can 30 be readily applied to a shoe-cleaning and scrubbing brush and combined therewith.

The several features of my invention and the various advantages derived from their use conjointly or otherwise will be apparent 35 from the following description and claim.

In the accompanying drawings, making a part of this application, and in which similar letters of reference indicate corresponding parts, Figure 1 represents in perspective 40 a view of a scrubbing-brush embodying my invention. Fig. 2 is a top view of the same brush.

I will now proceed to describe my invention in detail.

45 The body of the brush, although it may be made of any suitable material, is preferably made of wood. The sides and top may each be of any desired configuration. These do not, however, enter into my invention. A 50 plain and simple back, such as shown, with straight sides C^2 C^3 and rounded end C^4 , I prefer for economy of manufacture. This simple shape is also a very useful one.

D indicates the bristles, connected in any desired manner to the under sides of the 55 back C. The front end C^4 of the back extends no farther beyond the edge of the bristles there, than in a brush not embodying my invention. The end is preferably straight. Beginning with the top edge of the front end 60 between the points A A, I cut into the back in a plane downward and backward to or about to the middle of the thickness of the back—viz., to the line B B. From this line I again cut outward and downward to the lower 65 edge A A of the said front. I thus form two plain edges and four corners, each and all useful in cleaning, as hereinbefore indicated. As these corners are found on each side of the end of the back, it makes no difference 70 whether the one using the brush is a right or a left handed person, nor on which side the work happens to be. Some one of the corners is at all times available, and no time is lost in hunting a chip or old knife to do the scraping with. Again, it is to be observed that the broad upper edge A A of the end C^4 , sharpened, as it is, by the formation I have given to 75 it, is conveniently used as a scraper to clean any flat surface.

80 While the back may be composite, and also those parts particularly representing my invention be originally separate and be subsequently combined with and made a part of the back of the brush, yet the preferable 85 mode is to form these parts integral with the other portion or portions of the back.

The invention is applicable not only to scrubbing-brushes, but to blacking-brushes and to brushes used for similar or analogous 90 purposes, and the term "scrubbing-brush" as used in the claim is to be understood to include such brushes.

What I claim as new and of my invention, and desire to secure by Letters Patent, is— 95

A brush having a V-shaped groove in its back extending from the upper edge thereof downward and inward to the median line, and thence downward and outward to the lower edge of the back to form scraping edges, all 100 substantially as shown and described.

JOHN B. MARTIN.
